(57) **CLAIM**

I claim the ornamental design for a binocular telescope, as shown and described.

DESCRIPTION

FIG. 1 is an isometric view of a binocular telescope according to an embodiment of the invention;

FIG. 2 is a right-side view thereof;

FIG. 3 is a left-side view thereof;

FIG. 4 is a front view thereof;

FIG. 5 is back view thereof;

FIG. 6 is a top view thereof; and,

FIG. 7 is a bottom view thereof.

The broken line(s) shown in the drawings are for illustrative purposes only and form no part of the claimed design. The stippling and shading lines shown in the drawings represent the approximate three-dimensional contour of the design, and are not intended to indicate surface decoration. Portions of the binocular telescope that are not shown in the drawings form no part of the claimed design.
